UNITED STATES PATENT OFFICE

123,964

DESIGN FOR A TEXTILE FABRIC OR SIMILAR ARTICLE

Horace S. Sumerfield, Philadelphia, Pa., assignor to Herbert B. Newton & Co., Philadelphia, Pa., a corporation of Pennsylvania

Application September 29, 1939, Serial No. 87,427

Term of patent 3½ years

To all whom it may concern:

Be it known that I, Horace S. Sumerfield, a citizen of the United States, residing at Philadelphia, in the county of Philadelphia and State of Pennsylvania, have invented a certain new, original, and ornamental Design for a Textile Fabric or Similar Article, of which the following is a specification, reference being had to the accompanying drawing, forming part thereof.

The figure is a plan view of a textile fabric showing my design. The design is characterized by the fabric having a two-tone effect, which is a light and dark effect on a rough cloth, and the rough cloth is apparent when the face of the fabric is at an angle to the eye.

I claim:

The ornamental design for a textile fabric or similar article, as shown and described.

HORACE S. SUMERFIELD.
